TENT

Otakar Valasek, Chicago, Ill.

Application February 17, 1933, Serial No. 657,178

10 Claims. (Cl. 135—1)

This invention relates to tents, and one object of the invention, among others, is the provision of an improved tent structure which is featured by novel and extreme simplicity of assembly, and which is at the same time durable, rigid, and highly efficient in use. Another object is to provide an improved tent structure which has the advantage of being extremely economical to manufacture.

10 The ordinary tent structure involves center poles, ropes, stakes, and other paraphernalia which make the assembly and disassembly complicated and time consuming. The present invention embodies numerous features of novelty and is designed to provide a structure of the character above described which is poleless, ropeless, and stakeless. A tent made according to my invention is easily portable and capable of use indoors and outdoors, being particularly adapted to be set up, for example, in a room in a house where attachment to the floor is not permitted. By means of my invention a cloth covering may be provided with pockets, for example, with posts or ribs inserted in the pockets. 15 By locking means, one form of which has been selected to illustrate my invention, which is to be hereinafter described, a tent may be assembled in position by merely giving a few turns to a screw to tighten the same. By means of other concrete exemplifications, other simple means are provided for accomplishing the results hereinbefore indicated.

Another feature of my invention is that the ribs or posts need never be removed from the pockets of the fabric, and the frame and fabric may be in a simple manner collapsed into a convenient portable package.

Other objects and advantages will appear hereinafter.

40 The invention will be best understood by reference to the accompanying drawings, forming a part of this specification, and in which:

Fig. 1 is a perspective view of a preferred form of my invention, partly broken away to illustrate one of the supporting posts and the pocket therefor;

Fig. 2 is an enlarged sectional view of the upper portion of the structure shown in Fig. 1;

50 Fig. 3 is a plan view, partly broken away, of the structure shown in Fig. 2;

Fig. 4 is a plan view of the supporting plate;

Fig. 5 is a perspective view illustrating the means for attaching the tent covering to the stationary posts hereinafter described;

Fig. 6 is a vertical sectional view of a modified form of my invention;

Fig. 7 is a bottom plan view of the structure shown in Fig. 6;

Fig. 8 is a vertical sectional view of another modified form of my invention;

Fig. 9 is an elevational view of part of the structure shown in Fig. 8, showing the means for assembling and attaching the stationary posts;

Fig. 10 is a bottom plan view of the structure shown in Fig. 9;

Fig. 11 is a vertical sectional view of another modified form of my invention;

Fig. 12 is an elevational view of a part of the form shown in Fig. 11;

Fig. 13 is a bottom plan view of the form shown in Fig. 12; and

Fig. 14 is a vertical sectional view of another modified form of my invention.

As illustrated in the drawings, the preferred form of my invention shown in Figs. 1, 2, 3, 4, and 5 includes a covering 18 for the tent, which may be of canvas or any other suitable material, provided with pockets 19, of which in the preferred form there are six to form a tent having 20 six sides 20, as will hereinafter more fully appear.

The tent covering may be manufactured by cutting out portions of material each sufficient to make up one side of the tent and a pocket. One of these portions may be laid against another 25 of these portions to register with it in such a manner that the right side of the superimposed portion, for example, contacts the right side of the other portion. In other words, when the two portions are laid with their outside or right faces 30 against each other the wrong side, for example, of the top portion will be uppermost, and the wrong side of the under portion will be on the bottom. With the two portions in this relation the portions

at one end, in the superimposed condition described, may be stitched in two rows so as to form 35 a pocket. When this has been done and the top portion is pulled away from the bottom portion the two right sides will be exposed and the portions will be attached to each other in the manner shown in Fig. 5. Each pocket is closed by a 40 hem at the bottom to hold the covering in place when posts hereinafter described are inserted in the pockets.

Also provided is a locking plate 21 having apertures 22 and elongated recess slots 23. There are six of each of these, as is apparent from Fig. 4. Adapted to be extended through the apertures 45 22 are a plurality of posts 24. Each post 24 is provided with an L-shaped extension 25, and 50

55 55

each L-shaped extension 25 is provided with a downwardly extending leg 26. The relation between the members 24, 25, and 26 is clearly evident from the structure shown in Fig. 2. The arrangement is such that when each post 24 is inserted into an aperture 22 the downwardly extending leg 26 extends into an elongated recess slot 23. The position of the posts 24 in their natural condition is shown in dotted lines in Fig. 10. 2. It will be evident that after the posts 24 have been inserted in the apertures 22 they are then to be inserted in the pockets 19. Also provided is an aperture 27 in the locking plate 21, and adapted to be inserted in this aperture is a bolt 15 28 having a shoulder 29. The bolt 28 also has a threaded shank 30, and has threaded thereon a lock nut 31. Also provided is a clamping plate 32 centrally apertured as at 33. The arrangement is such that the bolt 28 is extended through 20 the aperture 33 in the clamping plate 32, and a wing nut 34 threaded on said bolt is adapted to be manipulated to move the clamping plate 32 downwardly against the L-shaped extensions 25 until the same are flat upon the upper surface of the locking plate 21. In this position the posts 24 will be swung outwardly from their former position, illustrated in dotted lines in Fig. 2, to the position shown in full lines in Fig. 2, and also in this position the downwardly extending leg 26 will have been moved downwardly into the elongated recess slot 23.

It will be apparent from the above description that the posts 24 are arranged in position with respect to the locking plate 21 with each post extending through one of the apertures 22. Each of the posts is inserted into one of the pockets 19 and then the clamping plate 32 is placed upon the bolt 28 and the wing nut is manipulated to force the clamping plate 32 against the L-shaped extensions 25 to force the posts 24 and the covering 18 outwardly to the position shown in Fig. 1. In the form shown in Fig. 4 elongated recess slots have been used, but in another form of my invention I utilize circular apertures. The elongated slots have the advantage of limiting or eliminating sidewise movement of the posts according to the depth of the apertures 22 and the elongated slots 23. The apertures 22 are of greater diameter than the diameter of the posts 24 to allow for the necessary pivotal movement which results from the action of the clamping plate.

In the form shown in Figs. 6 and 7, a cone-shaped locking member 35 is provided, which has bores 36. The posts used in this form of my invention are of different structure than the posts shown in the first form used to illustrate my invention. Adjacent the upper extremity of each post 37, as shown in Fig. 6, each post is provided with a shoulder 38 formed by making a U-shaped bend in the post, and each post is also provided with an upward extension 39. The lower face of the cone-shaped locking member 35 is provided with a series of grooves 40. The arrangement is such that after the posts have been properly inserted into the pockets of the tent covering each of the upward extensions 39 is inserted into a bore 36, and each shoulder portion 38 is moved into one of the grooves 40. It will be manifest that when properly arranged the posts will be locked in the position shown in Fig. 6 with each of the shoulders resting in one of the grooves. The angular relationship of the portions of each post 37 is clearly evident from Fig. 75

6. By this arrangement the inclined bore cooperates with the upward extension 39 of each post to cause the outward projection of the post, and the grooves of the member 35 cooperate with the shoulders of the posts to lock the same against lateral movement.

In the form used to illustrate my invention shown in Figs. 8, 9, and 10, a hollow cone member 41 is provided with outwardly projecting pockets 42 which may be attached to the cone member by electric welding or otherwise, or which may be made integral therewith, as by crimping or molding, or otherwise. In the form shown in Figs. 8, 9, and 10 each of the pockets is slightly larger at its downward end than at 15 its upper end, and also in the form shown in Figs. 8, 9, and 10 a V-shaped slit 43 is incorporated. In this form of the invention simple cylindrical posts 44 are employed, and after being inserted in the pockets of the tent covering the upward extremities of the posts which may be tapered are adapted to be inserted in the outwardly projecting pockets 42 of the cone-shaped member, in an obvious manner, and to be held firmly and rigidly therein. The slit functions to 25 provide resiliency for the structure.

In the form shown in Figs. 11, 12, and 13 a cone-shaped member 45 has provided in its outer conical surface a series of semi-cylindrical grooves 46. The posts 47 used in this form of 25 my invention are the same as the posts used in the form shown in Figs. 8, 9, and 10. In the form shown in Figs. 11, 12, and 13, a ringed clamping member 48, substantially conformed to the outer conical surface of the cone member 45, is provided, and the diameter of this member is somewhat larger than the diameter of the conical member 45 so as to allow the posts to be inserted in the grooves 46 and to allow the clamping member 48 to be moved downwardly 40 upon the conical member 45 and the posts when the posts are in the grooves to clamp the same.

From the foregoing it will be manifest that the posts are inserted into the pockets of the tent covering, and then the upper extremities of 45 the posts are located in the grooves and the clamping member 48 is thereupon placed upon the conical member and moved downwardly over this member with the posts in place in the groove. The grooves and the clamping member function 50 to maintain the posts rigidly in the position shown in Fig. 11, and to insure against deviation therefrom.

In the form shown to illustrate my invention in Fig. 14 a conical member 49 is provided which is substantially the same as the conical member illustrated in Fig. 6, excepting that the member is not provided with grooves like the grooves 40 of the form shown in Fig. 6. On the contrary, its bottom 50 is entirely flat. The conical member 49 is provided with a plurality of bores 51, and it will be manifest that simple cylindrical posts 52, after having been inserted into the pockets 19 of the tent covering, have their upper extremities inserted into the bores 51 of the member 49 to maintain the posts and the tent covering rigidly in the position shown in Fig. 14.

The operation of the structures of the various concrete exemplifications selected to illustrate the principle of my invention will be manifest 70 from the foregoing. With reference to the fabric and the pockets therefor, it is not necessary to remove the posts or ribs from the pockets, and in practice the same is never done. By the means hereinbefore set forth the frame and the 75

fabric may be collapsed into a convenient package ready to be set up in a very speedy and simple manner at any time anywhere. While I have illustrated certain concrete means in several forms 5 for applying the principle of my invention, an unlimited number of other forms applying the principle might be illustrated, but it will be obvious from the foregoing that other equivalent means may be employed. The forms selected to illustrate the principle are deemed sufficient for the 10 purposes of the present application to illustrate the substantial scope of my invention. For example, I have provided a screw in the form of the device shown in Fig. 1, and it is obvious that other 15 means may be provided for performing the same function. Obviously changes may be made, for example, in the post connections and in the plates without changing the principle of my invention. It will be obvious also, for example, that the screw 20 means in the structure shown in Fig. 1 may be operated otherwise, as from the bottom instead of from the top.

Also, while I have described a method of making the cover and pockets for the tent, the same 25 may be made by other methods. For example, a single sheet, properly cut, may be provided with a series of plaits and the plaits may then be stitched in a manner which will be obvious to those skilled in the art so as to provide the 30 requisite series of pockets.

Another method consists in cutting sections of material, each sufficient for one side and a pocket. One edge of one section may be lapped over the 35 edge of another section and a double seam stitched into the lapped edges to provide a pocket, as will be plain to those skilled in the art. It should be understood that the pockets will be hemmed or the entire tent may be hemmed at the bottom to maintain the covering in its proper 40 position when the posts are inserted in the pockets. Therefore, while I have illustrated and described preferred forms of construction for carrying my invention into effect, it will be distinctly understood that these are capable of variation 45 and modification without departing from the spirit of the invention. I, therefore, do not wish to be limited to the precise details of construction set forth, but desire to avail myself of such variations and modifications as come within the substantial 50 scope of the appended claims.

Having thus described my invention, what I claim as new and desire to secure by Letters Patent is:

1. In a device of the kind described, a supporting plate provided with apertures and slots, a plurality of posts said posts having angular extensions, and said extensions being provided with angular projections, the posts being adapted to be inserted in the apertures at their upper extremities, and the angular projections being adapted to be inserted in the aforesaid slots, and a clamping member adapted to move the posts outwardly at their lower extremities and to bear

against the extensions to force the projections into the slots and lock the posts.

2. In a device of the kind described, a supporting plate provided with apertures and slots, a plurality of posts said posts having angular extensions, and said extensions being provided with angular projections, the posts being adapted to be inserted in the apertures at their upper extremities, and the angular projections being adapted to be inserted in the aforesaid slots, a 10 clamping member adapted to move the posts outwardly at their lower extremities and to bear against the extensions to force the projections into the slots and lock the posts, and means for operating the clamping member. 15

3. In a device of the kind described, a positioning member having a plurality of external pockets, each pocket adapted to receive an end of a post therein.

4. In a device of the kind described, a positioning member, a plurality of posts, and a clamping member adapted to lock the posts against the positioning member said positioning member being provided with external means for positioning said posts relative to each other. 20

5. In a device of the kind described, a positioning member provided with a plurality of external grooves, a plurality of posts adapted to have their upper extremities severally fitted in said grooves, and a clamping member adapted to lock 30 the plurality of posts in the grooves on said positioning member.

6. In a device of the kind described, a tapering positioning member provided with a plurality of external grooves, a plurality of posts adapted to have their upper extremities severally fitted in said grooves, and a ringed clamping member adapted to lock the posts against the positioning member. 35

7. In a device of the kind described a plurality 40 of posts, means for positioning said posts with respect to each other, and clamping means adapted to cause the lower extremity of each post to be moved radially outwardly to its proper position and lock the entire structure.

8. In a device of the kind described a plurality of posts adapted to extend from the ground upwardly to support the usual tent covering, said posts being provided with angular extensions, positioning means for positioning the posts with 50 respect to each other, and means for locking the entire device.

9. In a device of the kind described a plurality of normally upright posts for supporting the usual tent covering and clamping means for moving 55 said posts radially to a definite position.

10. In a device of the kind described a supporting member and a plurality of tent posts adapted to extend upwardly from the ground and be positioned externally adjacent said supporting member and a clamping member for locking the posts against the supporting member. 60

OTAKAR VALASEK.
